UNITED STATES PATENT OFFICE.

EDUARD FRIEDEREICH FISCHER AND HARRY WILLIAM SCHMID, OF PHILADELPHIA, PENNSYLVANIA.

SAD-IRON HEATER.

SPECIFICATION forming part of Letters Patent No. 716,020, dated December 16, 1902.

Application filed March 25, 1902. Serial No. 99,837. (No model.)

To all whom it may concern:

Be it known that we, EDUARD FRIEDEREICH FISCHER and HARRY WILLIAM SCHMID, citizens of the United States of America, residing at Philadelphia, in the county of Philadelphia and State of Pennsylvania, have invented new and useful Improvements in Sad-Iron Heaters, of which the following is a specification.

Our invention relates to sad-iron heaters in which the sad-iron to be heated is supported upon a metallic support perforated at the bottom to allow of the circulation of currents of hot air and flame to come in contact with the surface of the sad-iron and the providing of a rest for holding a sad-iron while cooling, the heat-producing medium being gas or other like fuel.

The object of our invention is to provide an inexpensive and efficient device for heating and supporting sad-irons while in use. We attain this object by means of the device shown in the accompanying drawings, in which—

Figure 1 is a plan view of the upper surface of the device. Fig. 2 is an elevation of the heating-bed. Fig. 3 is an elevation of the complete device. Fig. 4 is a plan of the base-plate.

Similar characters refer to similar parts throughout the several views.

We make of metal a suitable base 6, with an ascending stem 7, to the top of which we secure the boss or center 4. This boss or center 4 is provided with a lateral rib 5 and an expanded portion C, forming a chamber B. The expanded portion C is embedded in a horizontal plate H and has openings A cut in its upper face communicating with the chamber B within the expanded portion C. The expanded portion C is at one end secured to a coupling D. This coupling D is provided with an opening E for the admission of air. The end of the coupling D is provided with means for securing an india-rubber hose thereto. In the coupling D at a convenient point we make a perforation G for the trans-

mission of gas into and beyond the opening E. At convenient points on the upper surface of the horizontal plate H we construct 50 lugs 2 near and above the expanded portion C to support a sad-iron to be heated. In the horizontal plate H within the rim 1 we make a series of perforations 8, which need not be of any prescribed form or number. On the 55 horizontal plate H we construct a rim 1, which extends about the sides of one portion of the horizontal plate H and is prolonged higher than the lugs 2. The expanded portion C has cut in the upper surface and above the 60 horizontal plate H openings A. The horizontal plate H is provided on the side away from the expanded portion C with a shelf 3, supported by the rib S'. This shelf 3 is provided with a series of openings 9, which may be of 65 any size or form. About the shelf 3 is made a low rim 3'.

Having described the parts of our invention, we proceed to explain the manner of using the same, to wit:

The several parts are securely put together in such manner that the openings A in the expanded portion C are uppermost, and between the lugs 2 a piece of rubber hose is then attached to the coupling D and gas admitted from an appropriate supply. The gas passes through the perforation G into the opening E, where it mixes with air to form a perfect combustion, and then passes around through the expanded portion C into the 80 chamber B and burns at the openings A. The degree of heat generated is regulated by the supply of gas admitted. The sad-iron to be heated is placed in the lugs 2 and allowed to remain as long as necessary. A second 85 sad-iron is placed on the shelf 3 while one is heating and is therefore gradually heated and replaces the heated sad-iron while the same is employed.

We do not claim as our invention sad-iron 90 heaters in the broad sense; but

What we do claim, and desire to secure by Letters Patent, is—

In a sad-iron heater, the combination of a

base provided with a standard, a horizontal plate supported upon said standard, said plate being provided with a shelf and heater on opposite sides of the standard, said heater comprising raised supports for irons, a burner situated between said supports, and a rim surrounding said supports and burner, all substantially as set forth.

In testimony whereof we affix our signatures in presence of two witnesses.

EDUARD FRIEDEREICH FISCHER.
HARRY WILLIAM SCHMID.
